UNITED STATES PATENT OFFICE.

BARNES NEVILLE WALLIS, OF WESTMINSTER, ENGLAND, ASSIGNOR TO AIRSHIP GUARANTEE COMPANY LIMITED, OF LONDON, ENGLAND, A BRITISH COMPANY.

MOORING MAST OR MOORING GEAR FOR LIGHTER-THAN-AIR AIRCRAFT.

Application filed January 4, 1926, Serial No. 79,076, and in Great Britain January 12, 1925.

This invention relates to mooring masts or mooring gear for lighter-than-air aircraft, hereinafter referred to as airships.

For the purpose of mooring an airship to a mooring mast it has been proposed to provide a fitting on the nose of the airship which is adapted to be coupled to a fitting at the top of the mast, the airship being adapted to be drawn into contact with the fitting on the mast head by means of a main anchoring or hauling down cable.

It has been found that, if a single cable is employed to draw the nose of the airship towards the mast, the airship, as soon as it approaches to within a certain distance of the mast, tends to kite or set up lateral hunting or over-rising forward movements, and, in order to prevent such dangerous movements of the ship it has been proposed to provide, in addition to the main anchoring or hauling down cable, a pair of side guy ropes or cables, each of which is attached at one of its ends to the nose of the airship, the other ends of the guy ropes being attached to anchor points situated to leeward of the mast and respectively to port and starboard of the airship, said anchor points being either provided on the ground or being situated on laterally projecting members on the mooring mast.

According to one feature of the present invention, and, in lieu of the customary single main hauling cable and the usual side guys, we provide a bridle composed of a pair of ropes or cables which extend from opposite sides of the nose of the airship and which are brought together, or close to one another, at their other ends, such ropes or cables being adapted to be simultaneously wound in so as to haul down the airship until it reaches, or is brought into close proximity to, the mooring mast or other anchoring point. It has been found that, if an airship is hauled down by a bridle composed, as aforesaid, of a pair of ropes or cables, the use of side guy ropes or cables can be dispensed with and the airship may be brought within any desired distance of the mooring mast or other anchoring point

without danger of over-riding, sailing or fouling the same. If, during the hauling in of the airship, its engines are run astern the stability of the vessel while being brought to the mast is increased.

According to a further feature of the present invention, and instead of rigidly attaching the nose of the airship to a fitting on the mooring mast, the airship is adapted to be moored in a non-rigid manner within a rotatable cradle situated on the mast and preferably disposed in a horizontal plane, so that the airship, when in position within the cradle, floats with a certain degree of flexibility relatively to the mast. To this end the said cradle may be constituted by a pair of projecting and horizontally disposed arms or members located on a revolving portion at the top of the mast, or said arms may be attached to the mast itself in cases where the whole structure is rotatably mounted on a foot step bearing, so that the arms can be brought into any desired position relatively to an approaching airship. The arms are set at a suitable angle, such as 90°, relatively to one another, and their inner ends are preferably spaced apart so as to obtain a cantilever effect. When the nose of the airship has been hauled down, for example from points situated at the centre of the mast and positioned at a suitable distance such as 30 feet above the said arms, until it is located at a suitable distance (e. g. 60 or 70 feet above said arms) ropes or cables are let down from the airship or drawn out by the bridle ropes, from points situated on opposite sides of the nose thereof. Said ropes may be caught by operators and attached to other mooring ropes or cables, hereinafter termed mooring warps, carried on the arms of the mast, the ropes being then drawn up so that they carry the mooring warps with them and the mooring warps being then attached to fittings located on either side of the nose of the airship contiguous to the part thereof through which the main hauling down ropes are passed. Auxiliary hauling down gear such as winches or capstans, are provided, for example, on

said arms, and on the winches being actuated the airship is hauled down further by means of the mooring warps attached to each side of the nose thereof until it is positioned between the said projecting arms. Alternatively ropes or cables may be let down from points situated on opposite sides of the nose of the ship, said cables being caught by operators positioned on the arms 10 and led respectively through fairleads or the like at the extremity of each arm to suitable hauling down gear, such as winches or capstans also situated for example on said arms. On the winches being actuated the airship is 15 hauled down further until it is positioned immediately above or between the said projecting arms, whereupon the mooring warps which have been prepared in readiness and which are carried respectively on each of the 20 said arms are attached to anchor points such as hooks or shackles situated on opposite sides of the nose of the ship, said warps or cables being then tightened or wound in as before by means of winches or the like so 25 as to haul down the airship and simultaneously bring the same closely within the cradle. The main hauling down ropes, or, in the case of the last mentioned method, the main and auxiliary hauling down ropes may 30 then be disconnected from the airship so that it is only attached to the arms by said mooring warps. Consequently the airship is held in a non-rigid manner and rides with a certain flexibility of movement in certain 35 directions while being constrained against movement in a forwardly or rearwardly direction. The mooring arrangements also ensure complete stability of the airship and eliminate the objectionable oscillating movements which have created trouble in other systems.

In addition to the auxiliary hauling down cables a further pair of cables (hereinafter termed the back haul cables), may be let 40 down from a single point or from points located on opposite sides of the nose of the airship in front of the points from which the auxiliary hauling cables are let down or to which the mooring warp are attached, 45 said back haul cables being received by other operators on the arms who take up the slack of the said cables as the airship is drawn down to the cradle. Should, however, a dangerous movement of the airship be initiated the winding down operation is 50 stopped and said other operators simultaneously locate a bight of each of the back haul cables round anchoring points on each arm. The airship is thus steadied by being 55 held at two fixed points until such dangerous movement ceases so that any tendency to foul or over-ride the mast is thereby prevented.

In order that the said invention may be 60 clearly understood and readily carried into

effect, the same will now be described more fully, with reference to the accompanying drawings, which show, partly diagrammatically, a mooring mast and its associated hauling down and mooring ropes constructed and operating according to the present invention, together with a diagrammatic illustration of one method of utilizing the same to haul down an airship and attach it in the moored position to the mooring mast the nose only of the airship being shown:—

Figure 1 is a side elevation of the mooring mast mounted upon a monitor, and shows the airship in the act of being hauled down into the moored position.

Figure 2 is a plan view showing the bridle ropes in full lines, (the mast being omitted), and in, dotted lines, the limiting position of the bridle ropes after they have entered the mast head guide pulleys.

Figure 3 is a side elevation showing the airship after it has been hauled down into close proximity to the mooring mast by means of the bridle ropes as also the mooring warps in the act of being drawn up from the projecting arms of the mast in order that they may be attached to opposite sides of the nose of the airship, and

Figure 4 is a plan of Figure 3.

Figure 5 is an elevation;

Figure 6 is a side elevation, and

Figure 7 is a plan, showing the mooring warps attached to opposite sides of the nose of the airship.

Figure 8 is an elevation,

Figure 9 is a side elevation, and

Figure 10 a plan showing the airship in the act of being hauled down into the moored position.

Figure 11 is a side elevation,

Figure 12 is a plan, and

Figure 13 is an elevation showing the airship in the moored position.

Figure 14 is a sectional elevation showing more clearly certain details of the rotating head of a slightly modified form of mooring mast the airship being in the moored position;

Figure 14^a is a front view of the guide pulleys for the main hauling down ropes.

Figure 15 is a plan of Figure 14, and Figure 15^a is a detail view showing in end view the pulleys and bollards provided at the extremities of each arm of the mast.

Figure 16 is a sectional elevation on an enlarged scale of the mast head combined roller and thrust bearing, and

Figure 17 is a section on an enlarged scale of one of the rollers on the rotating mast head.

The main hauling down rope comprises a single portion a^1 which may for example be 500 or 600 feet in length, and which is joined to a bridle portion formed by two 130

ropes a^2 , a^2 running to winches or mooring points a^3 , a^3 situated on opposite sides of the nose of the airship, E, preferably at the first transverse frame e . The length of the 5 bridle portion a^2 , a^2 , can be varied as may be found necessary but approximately 150 feet is a suitable length. It is considered that this length is sufficient to damp out lateral oscillations even when the ship is at a 10 considerable distance from the mooring mast for, in the event of the ship getting off wind under these conditions, a large restoring moment is set up owing to the slackening of the weather bridle rope. The bridle 15 a^2 , a^2 is stowed on suitable winches in the airship while the single rope a^1 is carried on a further winch conveniently situated at the bottom of the first transverse frame, the single rope a^1 and double ropes a^2 , a^2 being 20 paid out in the usual manner when it is desired to effect a landing. According to this embodiment of the invention no other apparatus is carried in the airship herself but hooks, shackles or their equivalent are provided in the neighbourhood of the two points 25 a^3 , a^3 to which the bridle ropes a^2 , a^2 are attached, for the connection thereto of the masthead mooring warps B and C. The mooring warps B and C are carried on each 30 of the two arms f , f of the mooring mast F, and D, D are ropes carried on the airship which are attached respectively to each rope a^2 of the bridle, these ropes D, D being paid out by the bridle when the latter is well 35 within the mast head pulleys and being attached by operators on the mast to the ropes B and C, the ropes D, D being then hauled up to the airship and the warps B and C attached to hooks or shackles on opposite sides 40 of the nose of the airship.

The mooring mast F comprises a fixed portion f^2 , and a rotatable portion f^3 which latter carries the two arms f , f the rotating portion f^3 consisting of a four sided pyramid carried on roller and thrust bearings G at the apex where it rests upon the fixed portion f^2 , the construction of the roller and thrust bearing being clearly shown at Figure 16. Two platform levels are provided, 45 the upper one f^4 being situated at a convenient height for the control platform and the lower one f^5 at the base of the pyramid forming a landing level for the passenger lift. At the upper platform f^4 are placed a 50 powerful brake and locking gear for preventing rotation of the movable portion f^3 when desired, and provision can also be made for a governor or automatic type of 55 brake designed to check rotation of the masthead in a smooth and easy manner under the influence of lateral pull from the airship during the process of landing. The lower platform f^5 is utilized as a base for a roller H and roller path H^1 which, taken in 60 conjunction with the upper journal and thrust

races G, stabilizes the moving portion f^3 on the fixed portion f^2 . The large distance separating the bearing systems ensures light frictional loading when the mast head is in operation. 70

From the pyramid thus formed the arms f , f project horizontally making an angle of 90° with each other along their inner edges; these arms being of such dimensions that each forms an enclosed passage giving access 75 to the airship at the same level as the access platform in the ship herself.

At the extremities of the arms and also at a point somewhat nearer to the axis of the mast suitable fairleads i , i , pulleys i^1 , i^1 and 80 bollards i^2 , i^2 are provided for running in the mast head warps, while the apex of the pyramid carries guide pulleys j , j of large dimensions for the main hauling ropes a^2 , a^2 . The top bearing T of the rotating portion f^3 85 is made in the form of a hollow shaft g^1 of approximately one foot in diameter through which the main hauling ropes a^2 , a^2 pass to a winding engine a^4 situated at the foot of the mast. The ropes pass through a guide tube 90 fixed in the passenger lift L (Figure 15) which is necessarily eccentrically mounted in the mast so as to accommodate the counter-weight L. The aforesaid arrangement of 95 bridle and hauling down ropes provided on the airship thus makes it possible to provide a single drum winding engine a^4 of the usual type at the mast foot so that the advantage of the bridle system is secured without the additional complication of having to wind 100 twin ropes.

The controls for the winding engine are situated on the upper platform f^4 of the rotating portion f^3 of the mooring mast.

Two auxiliary winding engines or motors 105 of small size, for example 10 H. P. each, are situated either at the masthead as shown or at the mast foot for operating the mooring warps B and C. The ropes C, C may be connected to two winding drums M^1 operated 110 by one auxiliary motor, while the ropes B, B are connected to other drums M operated by a second auxiliary motor, suitable fairleads and pulleys being provided.

The mast illustrated is one which has been 115 designed for installation on a monitor but the system is equally applicable to land installations in which case the mast may be either a steel or ferro-concrete structure. The method of operation is in both cases the 120 same.

When carrying out a landing by the aforesaid system the main hauling-in rope a^1 is dropped from the airship to a marked position on the ground to which the masthead 125 rope has been laid in the usual manner. In the case of a sea operation the masthead rope would be carried by a motor boat and the ship's rope a^1 would be provided with a floating buoy which would be picked up by 130

the boat's crew. When connection has been established, hauling-in is begun and is carried on until the bridle portion a^2 , a^2 of the airship's rope a^1 is well within the masthead pulleys as illustrated at x Figure 1. When the position shown in this figure has been reached the bridle ropes a^2 , a^2 carry out with them automatically the two hemp lines D, D, one on either leg of the bridle which are detached by attendants at the masthead and coupled respectively to the shackle fitting of the ropes B and C lying in readiness on the projecting arms f, f.

10 The hemp ropes D, D are then hauled up 15 into the airship carrying with them the ropes B and C, the latter ropes being made fast at the special positions provided at the first transverse frame.

At the same time hauling on the main rope 20 a^1 is proceeded with until the ship's bridle a^2 , a^2 has entered the masthead as far as the point y (Figure 1). A true view of the bridle under these conditions is given in plan view at Figure 2. When the bridle ropes 25 reach the limiting position, hauling on the main engine a^4 ceases and the length of bridle rope stretching between the masthead and the ship remains constant for all further operations. The auxiliary motors 30 controlling the winding drums M, M¹ are now put in operation and hauling down commences, the principal work being done in the first instance by the motor connected to the drum M¹ on which the mooring warp C is 35 wound. When once the airship has passed the position in which the bridle ropes are approximately horizontal, the ropes C quickly provide a restraint to forward motion, and the ship as she approaches closer to the 40 masthead enters what may be termed a safety zone when the length of ropes C become such that whatever the relative motion of the mast and ship may be it is impossible for fouling to occur.

45 An investigation of the stresses in the various ropes during the intermediate stages illustrated in Figures 5 to 10 will show, however, that the airship is held in an essentially stable manner, all ropes being kept 50 continuously in tension under the influence of drag from the astern running propellers.

After passing the stage illustrated in Figures 8, 9 and 10 the ropes C become a safety device only and hauling down to the final 55 position is carried out by ropes B, the motor attached to ropes C following up as necessary. The advantage of using a hydraulic motor over other types will be appreciated in this connection as this form of power 60 plant enables a constant following up tension to be maintained by the motor without further attention on the part of the operator. Hauling down proceeds on ropes B until the levels of the landing platforms 65 in the ship and on the masthead coincide

(Figures 11 to 15). It should be noted that during the process of hauling down no attention whatever is required to the main hauling ropes, as the length of the bridle automatically ensures that the ship shall 70 come home in the correct position.

An examination of the system of ropes illustrated in Figures 11 to 13 will show that the vessel is now permanently secured by a three point suspension on either side; and should only a short stay at the masthead be anticipated it is merely necessary to lock the drums on the winding engines to secure the ship in the position shown. For a prolonged stay or in the event of bad weather, 80 arrangements are provided for replacing the hauling ropes and mooring warps by permanent and heavy warps carried on the masthead. These warps may consist of a wire cable provided with a length of adjusting chain cable and bottle screws for tensioning, the hauling ropes a^1 and a^2 and the mooring warps B and C on each side of the ship being attached to a single shackle at the ship end, and being secured 90 in close proximity to the points from which the hauling ropes themselves are led at the mast end.

A modified method of mooring the airship to that illustrated with reference to the drawing consists in providing each laterally projecting arm, towards its inner end, and in addition to the capstans for hauling down the airship after it has been brought into a position where it is situated above the 100 laterally projecting arms, with a pair of winches over which the warps by which the airship is to be finally secured to the said arms are passed, one end of each warp being preferably brought from one winch 105 drum through a fairlead at the front or projecting end of the arm back to the drum of the second winch. A bight or looped portion is thus formed in readiness to be located over the hook, shackle or other fitting on each side of the nose of the vessel when the latter has been hauled down to about platform level. In order to cause the warps to complete the hauling down movement of the airship to platform level, each 110 warp, instead of being led directly from one winch drum to the other may be formed in two portions, each portion from one of the winch drums being brought round a pulley and its ends connected to a point on the arm situated at some distance below platform level. The two pulleys may be connected together by an eye or shackle adapted to be looped over the fitting on the nose of the airship, or instead of using two 115 pulleys a single pulley may be employed, a connection being taken as before from one cable to a fixed point on the arm and the end of the cable from the other winch drum being connected directly to the pulley. Ow- 120 125 130

ing to either of these arrangements the ship will be hauled down slightly at the same time as it is being brought into the space between the said arms. The airship itself 5 may be fitted at the foremost transverse frame with capstans, or, alternatively, with a winch having a pair of drums, or else a pair of winches may be provided, over each drum of which the cables of the bridle are 10 wound, the cables being adapted to be led through fairleads or the like on each side of the nose of the ship. The outer ends of the bridle cables may be joined together at their ends by shackles and stowed during 15 flight in a suitable trap release capable of being operated from the control position, the latter being conveniently positioned within the nose of the ship.

The operation of this last mentioned modified arrangement is as follows:—On the airship approaching the mooring mast, the bridle cables are released from the trap previously referred to on the nose of the airship, and connected to a pair of cables which are 20

led round the guide pulleys at the top of the mast to the winding engines or winches. To facilitate this operation the ends of the bridle ropes may be detachably connected together and painted respectively red and 25

green or marked in some other distinctive manner so as to indicate the side of the ship from which they are led, and a sandbag or buoy may be attached thereto so that the cable ends may readily be picked up by an 30

operator on land, or, in cases where the mooring mast is provided on a vessel at sea, by means of a fast boat, and readily connected to the ends of the correspondingly marked pair of ropes from the masthead. 35

Alternatively, the bridle cables may be connected to the masthead cables, without the intervention of a landing party or a fast motor boat, by directing the airship slowly 40 across the mast with the bridle cables hanging down, so that they are swung between the projecting arms of the rotating head, whereupon they are picked up by attendants and secured to the ends of the masthead cables. The ship is then hauled in by means 45

of the winch or winding engine situated at the foot of the mast until it is situated at a suitable distance above the masthead. The hauling in of the bridle cables is then stopped so that the airship rides on the 50

bridle cables, for example, at approximately 55 feet from the masthead and with the bridle cables, making an angle of about 45° therewith and at a height of about 60 or 70 feet above the projecting arms. From large 60

gangway ports near the points of attachment for the bridle cables light pilot ropes or the like to which are attached the auxiliary hauling down cables, as also back-haul cables 65

where such are used, may then be thrown across each of the projecting arms situated 70

below, these ropes being caught by attendants. After the pilot ropes which are attached to the auxiliary hauling down cables have been passed through the fairleads and round the capstans, the ship is hauled down until it is situated above or between the laterally projecting arms, whereupon the warps are connected by the attendants on the platform to the fittings on each side of the ship and the warp winches are actuated so as to draw the ship down to platform level and make it fast between the projecting arms of the mooring mast. An ordinary type of gangway can then be run aboard on either side so as to establish double communication between the ship and the platform and lift on the masthead. On leaving the mast, quick releases are operated to free the shackle point from the warp cables so as to allow the ship to float up and move astern, 85

The operation of releasing the airship by the method described with reference to the accompanying drawings may be performed as follows:—On occasions when it has not

been necessary to apply the system of warp referred to above, the release of the ship is carried out in the following manner. The fitting to which the ropes B and C are attached at each side of the airship may consist of a standard type of slip, the two sides 90

being operated simultaneously from a central control position in a similar manner to that employed when slipping the falls of a boat at sea. The airship then remains attached to the mooring mast by her bridle 95

rope a^2 , a^2 , and will rise upwards and astern into the position illustrated in Figures 3 and 4. The bridle rope will already have been prepared for release, as after landing, 100

a stopper is placed on the bridle at the point of the splice. Access to this point inside the mooring mast is readily attained by suitable operation of the lift, and the tension being removed from the drum of the main winding engine, the shackle joining the single rope a^1 of the airship to the single rope 105

of the winding engine can be uncoupled and reunited by means of a small piece of twine. The brake is again applied to the drum of the winding engine shortly before releasing 110

the stopper rope when a ship is about to leave the mast, and after the slipping of the ropes B and C the ship is eased astern on the bridle a^2 , a^2 by means of the brake 115

on the winding engine drum. Should everything prove in order, the ship is finally to proceed, and her hauling-in rope a^1 draws out of the mooring mast, snapping the twine coupling in the process. Re-stowage of the ship's hauling down ropes 120

and mooring warps is then carried out in the usual manner whilst in flight.

Should the permanent masthead warps have been in use the ship's bridle rope will 125

have been stowed whilst at the masthead, and 130

in this case slipping of the mooring warps is carried out simultaneously on both sides of the ship by means of the gear above referred to, it being noted that the three ropes on each side are secured to a single fitting. Apparatus for recording the vertical re-action at the nose of the ship may be provided in the fittings for the attachment of the ropes.

10 The system of ropes shown has been designed with the express object of reducing the stress set up by heavy and gusty winds in the airship's structure when the airship is secured to the mast. Ample factors of safety have been allowed under all conditions. The limiting cases have been taken as hauling-in in a gusty wind of 60 M. P. H.; and when secured it has been assumed that the ship may oscillate through an angle of 20° under the influence of a wind of equal intensity.

15 It should be noted that the torsional restraint imposed upon the airship is of distinct advantage in reducing the stresses set up when yawing, and owing to the large diameter of the ship at the points of attachment the resultant loading induced in both ship and mast is of almost negligible amount.

20 The system of mooring forming the subject of the present invention has the advantage that, when landing on a mast carried on a floating base at sea, both the cables a^2 , a^2 , comprising the bridle can be picked up as a single unit, while the method of hauling in the airship by means of a bridle to the masthead gives complete stability and eliminates oscillating movements which have created trouble in the past in other systems.

25 When in the position on the masthead the floating airship is not attached in a rigid manner, as it is capable of slight floating movements although restrained against forward or rearward movements.

30 Should the ship sink by the tail a suitable device may be provided for automatically bringing it back to a level keel. Passengers can also be landed through the nose of the airship and carried by means of a lift to the level of embarkation, while complete circulation of passengers can be provided for so as to enable them to be embarked and disembarked simultaneously, thus shortening the duration of stoppage at the mast.

35 The system also enables the whole of the control apparatus to be kept under constant supervision and to be readily accessible for such repairs as may be necessary. Furthermore, the mooring mast can be fitted with a lightning conductor P some 70 to 100 feet in height, a point which is of considerable importance if the mast is intended for use in tropical countries. Mooring an airship under all conditions to a mast fitted to a

40 floating base such as a monitor is also ren- dered, by the present invention, as simple a matter as mooring an airship to a land mast, and it is also possible to use the same mast for accommodating any type or size of airship from the largest commercial naval air- 70 ship of the rigid type to the smallest sea scout of the non-rigid type.

45 A further advantage of this new system of mooring is that although in the single wire system and when mooring to a mast 75 carried in a sea-going vessel, it is necessary that during the actual process of mooring the latter is either steaming into or lying with its bow pointing directly to the wind, with the bridle method herein described, 80 such a procedure is unnecessary, for mooring can be satisfactorily carried out whether the sea going vessel be at anchor lying off the wind or underway and not steaming directly into the wind. 85

50 What I claim and desire to secure by Letters Patent of the United States is:—

1. Apparatus for mooring lighter-than-air aircraft comprising a mooring mast, winding gear associated with said mooring mast, a pair of cables extending from opposite sides of the aircraft which is to be moored, the free ends of said cables being simultaneously wound in during the mooring operation by said winding gear so as 95 to haul down the aircraft until it is brought into close proximity to the mooring mast.

2. Apparatus for mooring lighter-than-air aircraft comprising a mooring mast, a cradle at the top of said mooring mast, 100 winding gear associated with said mooring mast, a pair of cables extending from opposite sides of the aircraft which is to be moored, the free ends of said cables being simultaneously wound in during the mooring operation by said winding gear so as to haul down the aircraft until it is brought into close proximity to the mooring mast and located above said cradle. 105

3. Apparatus for mooring lighter-than-air aircraft comprising a mooring mast, a rotatable cradle at the top of said mooring mast, winding gear associated with said mooring mast, a pair of cables extending from opposite sides of the aircraft which is 110 to be moored, the free ends of said cables being simultaneously wound in during the mooring operation by said winding gear so as to haul down the aircraft until it is brought into close proximity to the mooring mast and the nose thereof located above 115 said rotatable cradle.

4. Apparatus for mooring lighter-than-air aircraft comprising a mooring mast, a cradle at the top of said mooring mast, 120 winding gear associated with said mooring mast, a pair of cables extending from opposite sides of the nose of the aircraft which is to be moored, the free ends of said cables being simultaneously wound in during the 125

mooring operation by said winding gear so as to haul down the aircraft until it is brought into close proximity to the mooring mast and the nose thereof located above said cradle, and means for hauling down the airship until the nose thereof is located within said cradle.

5. Apparatus for mooring lighter-than-air aircraft comprising a mooring mast, a cradle at the top of said mooring mast, winding gear associated with said mooring mast, a pair of cables extending from opposite sides of the nose of the aircraft which is to be moored, the free ends of said cables being 10 simultaneously wound in during the mooring operation by said winding gear so as to haul down the aircraft until it is brought into close proximity to the mooring mast and the nose thereof located above said 15 cradle, means for hauling down the airship until the nose thereof is located within said cradle, and means for attaching the airship to said cradle.

6. Apparatus for mooring lighter-than-air aircraft comprising a mooring mast, a pair of projecting and horizontally disposed arms attached to a rotatable portion at the top of the said mooring mast, means for rotating said portion at the top of the mooring 20 mast, a pair of cables extending from opposite sides of the aircraft which is to be moored, the free ends of said cables being brought from the aircraft to the mast and simultaneously wound in by said winding gear so as to haul down the aircraft until it is brought into close proximity to the mast.

7. Apparatus for mooring lighter-than-air aircraft comprising a mooring mast, a pair of guide pulleys at the top of said mooring 25 mast, winding gear associated with said mast, a cradle on said mast, and a pair of cables extending from opposite sides of the aircraft which is to be moored, the free ends of said cables being brought from the aircraft to the mast and simultaneously wound over said pulleys by said winding gear so as to haul down the aircraft until it is brought into close proximity to the mast.

8. Apparatus for mooring lighter-than-air aircraft comprising a mooring mast, a pair of guide pulleys at the top of said mooring mast, winding gear associated with said mast, a cradle on said mast, a pair of cables extending from opposite sides of the aircraft which is to be moored, the free ends of said cables being brought from the aircraft to the mast and simultaneously wound over said pulleys by said winding gear so as to haul down the aircraft until it is brought into close proximity to the mast and means for hauling down the nose of the airship still further until it is located within said cradle.

9. Apparatus for mooring lighter-than-air aircraft comprising a mooring mast, a pair

of guide pulleys at the top of said mooring mast, winding gear associated with said mast, a cradle on said mast, a pair of cables extending from opposite sides of the aircraft which is to be moored, the free ends of said cables being brought from the aircraft to the mast and simultaneously wound over said pulleys by said winding gear so as to haul down the aircraft until it is brought into close proximity to the mast, 70 means for hauling down the nose of the airship still further until it is located within said cradle and means for attaching the aircraft to the said cradle.

10. Apparatus for mooring lighter-than-air aircraft comprising a mooring mast, a pair of guide pulleys at the top of said mooring mast, winding gear at the base of said mast, a pair of projecting and horizontal arms rotatably attached to said mooring mast and located beneath said pulleys, a pair of main cables extending from opposite sides of the aircraft which is to be moored, the free ends of said main cables being brought to said mast and simultaneously wound in 80 over said pulleys by said winding gear so as to haul down the aircraft until it is brought into close proximity to the mast, and auxiliary cables associated with each of said projecting arms for hauling down the aircraft still further until the nose thereof is located above said arms.

11. Apparatus for mooring lighter-than-air aircraft comprising a mooring mast, a pair of guide pulleys located at the top of said mooring mast, winding gear at the base of said mast, a pair of projecting and horizontal arms rotatably attached to said mooring mast and located beneath said pulleys, a pair of main cables extending from opposite sides of the aircraft which is to be moored, the free ends of said main cables being brought to said mast and simultaneously wound in over said pulleys by said winding gear so as to haul down the aircraft until it is brought into close proximity to the mast, auxiliary cables associated with each of said projecting arms for hauling down the aircraft still further until the nose thereof is located above said arms, and back haul cables extending between the aircraft and the mast the slack of which is taken in as the aircraft is hauled down into position between the said arms.

12. Apparatus for mooring lighter-than-air aircraft comprising a mooring mast, a pair of guide pulleys located at the top of said mooring mast, winding gear at the base of said mast, a pair of projecting and horizontal arms rotatably attached to said mooring mast and located beneath said pulleys, a pair of main cables extending from opposite sides of the aircraft which is to be moored, the free ends of said main cables being brought to said mast and simultaneously 120 125 130 wound over said pulleys by said winding gear so as to haul down the aircraft until it is brought into close proximity to the mast, and means for hauling down the nose of the airship still further until it is located within said cradle.

wound in over said pulleys by said winding gear so as to haul down the aircraft until it is brought into close proximity to the mast, auxiliary cables associated with each of said projecting arms for hauling down the aircraft still further until the nose thereof is located above said arms, and mooring

warps on each of said arms adapted to be attached to the nose of the aircraft when located above said arms for hauling down ¹⁰ the airship and mooring her in final position between the said arms.

BARNES NEVILLE WALLIS.
